UNITED STATES PATENT OFFICE

166,423

HAT

Henry F. Stec, Chicago, Ill.

Application September 25, 1951, Serial No. 16,736

Term of patent 3½ years

(Cl. D3—13)

To all whom it may concern:

Be it known, that I, Henry F. Stec, a citizen of the United States, residing at Chicago, in the county of Cook, and State of Illinois, have invented a new, original, and ornamental Design for a Hat of which the following is a specification, reference being had to the accompanying drawing, forming part thereof.

The figure on the drawing is a top, perspective view of a hat showing my new design.

The undisclosed portion of the hat presents a similar appearance as the side shown.

I claim:

The ornamental design for a hat, substantially as shown and described.

HENRY F. STEC.
